UNITED STATES PATENT OFFICE.

ERNST H. HUENEFELD, OF CINCINNATI, OHIO.

DESIGN FOR AN OVEN-DOOR.

No. 40,062.

Specification for Design.

Patented June 15, 1909.

Application filed April 16, 1909. Serial No. 490,433. Term of patent 14 years.

To all whom it may concern:

Be it known that I, ERNST H. HUENEFELD, a citizen of the United States, residing at Cincinnati, in the county of Hamilton and State of Ohio, have invented a new, original, and ornamental Design for Oven-Doors, of which the following is a specification, reference being had to the accompanying drawings, forming a part thereof.

Figures 1 and 2 are views in front and rear

elevations of an oven door, showing my new design.

I claim:

The ornamental design for an oven door, as shown.

ERNST H. HUENEFELD.

Witnesses:

W. E. HUENEFELD,
JOHN R. CARTER.
